FIG.1

FIG.2

FIG.3

FIG.4

FIG. 1 is a front or outside view of a wheel cover embodying my new design;

FIG. 2 is a top view of the wheel cover shown in FIG. 1;

FIG. 3 is rear or inside view of said wheel cover; and

FIG. 4 is a cross-sectional view taken on line 4—4 of FIG. 3.

The broken lines in FIGS. 2 and 4 indicate the extent of the wheel-securing flange shown at the center in full lines.

I claim:

The ornamental design for a wheel cover or similar article, substantially as shown and described.
